FRANK MOORE AND ALEXANDER GRAY, OF TORONTO, ONTARIO, CANADA.

CARBURETOR ATTACHMENT.

1,421,530.

Specification of Letters Patent.

Patented July 4, 1922.

Application filed January 24, 1921. Serial No. 439,359.

To all whom it may concern:

Be it known that we, FRANK MOORE and ALEXANDER GRAY, both subjects of the King of Great Britain, and both residing in the 5 city of Toronto, county of York, Province of Ontario, Canada, have jointly invented certain new and useful Improvements in Carburetor Attachments, of which the following is a specification.

10 Our invention relates to improvements in carburetor attachments of that type which performs the function of agitating and mixing the charge of explosive mixture and air as it passes from the carburetor into and 15 through the manifold, and the object of the invention is to more thoroughly agitate and mix the air and the charge of explosive mixture by preventing the occurrence of any unoccupied passage ways straight through 20 the attachment through which a stream or current of non-agitated air and explosive mixture can even momentarily flow. Another object of the invention is to provide 25 an improved means for mounting the attachment in place.

Fig. 1 is a fragmentary elevational view of a carburetor with the engine intake pipe or manifold shown in section, and showing our improved attachment, and attaching 30 means therefor, mounted in place. Fig. 2 is a plan view of the preferred form of supporting means for the attachment, in the form of a metal gasket, and Fig. 3 is a plan view of an alternative form of the attachment.

35 In the drawings, like characters of reference refer to the same parts.

It is well known in the prior art that carburetor attachments comprising a plurality 40 of vanes have been mounted on a common spindle and located within the manifold or engine intake pipe. Frequently two distinct sets of vanes are each provided with a hub, and the angular disposition of these vanes to 45 their respective hubs is such that the rotary mixing devices are caused to rotate in opposite directions by the force of the fluid drawn through the manifold or intake pipe. From 50 experience we have found it frequently occurs that a clear unrestricted passage way longitudinally of the manifold or intake pipe is presented through which a current of air and explosive mixture can unrestrictedly 55 flow, and the result is that during a given period of time a considerable amount of un-

agitated air and explosive mixture has been taken into the cylinder.

In putting our invention into practice we employ two or more rotary mixing devices which positively and definitely rotate at different speeds, either in the same or in opposite directions and thereby prevent, even momentarily any said unrestricted passage-way between the rotary mixing devices longitudinally of the manifold or intake pipe.

We obtain the differential in rotation in various ways. Our preferred manner of reaching this result is to dispose the vanes of the rotary mixing devices at different angles to the axis of rotation of the device, and another way is to increase the area of the vanes in one rotary mixing device and decrease the area of the vanes in the companion rotary mixing device. In the latter case the angle of inclination of the vanes to the axis of rotation of the said devices may be the same.

The illustrated constructions we are now about to describe are merely exemplary means whereby the object of the invention is carried out, and it must be clearly understood that we do not confine ourselves to the construction shown and described.

Although the mounting means illustrated is that preferred, still we do not confine ourselves to using the same.

A is any suitable type of carburetor from which the pipe B leads. This pipe is provided with a flange C. D is the flange of the manifold or intake pipe E. Between the flanges C and D are placed the slotted ends F of the gasket G, and these parts are secured in place by any suitable means such as bolts H. By reason of the slots I the gasket G straddles the bolts H.

95 This gasket is provided with the central opening 2 through which the explosive mixture passes in the usual way, and forming preferably an integral part of said gasket and bridging the opening 2 and vertically positioned thereabove, is a bridge 3. Mounted in the central opening 4 formed in said bridge is a spindle 5 on which is mounted the hubs 6 and 7, which are preferably held in spaced relationship in respect to each other and in respect to the bridge 3 by the rings 8. Carried by the hubs 6 and 7 are a plurality of vanes 9. The vanes of the hub 6 occupy substantially the same angular position to the spindle 5, and the vanes of

100

105

110

the hub 7 occupy a common angular position in respect of the spindle 5 but different to that of the vanes of the hub 6. The result is that the two rotary mixing devices while 5 they will rotate in the same direction will essentially and at all times rotate at different speeds.

10 is the head of the spindle 5 and 11 is the nut screwing on the lower end thereof 10 and against the underside of the bridge 3.

While it forms no part of our invention, it will be understood that the most improved construction for reducing friction will be used in all forms of our device.

15 In Fig. 3 we show two rotary mixing devices 12 and 13 mounted to rotate on the spindle 5'. One of these mixing devices has four vanes or blades, and the other has three, and they are supposed to be placed 20 at the same angular position to the spindle 5'. The area of the blades 14 of the rotary mixing device 12 is greater than the area of the blades 15 of the rotary mixing device 13. There are four vanes or blades 14, and three 25 vanes or blades 15 in the example just set forth. Naturally the speed of rotation of the mixing device 12 will be essentially and always greater than that of the mixing device 13. Since the mixing device 12 will 30 preferably be the one nearest the carburetor certain vanes thereof have been broken away and shown in dotted position in Fig. 3.

While we have illustrated and described 35 our mixing device as preferably used in

connection with internal combustion engines it must be understood that we do not confine ourselves to this field of use for our invention.

To get the best result, the diameters of the 40 mixing devices will be substantially the same, and they will operate as closely as possible to the inner walls of the pipe E so as to reduce to a minimum the passage-way between said pipe and said mixing devices. 45

What we claim as our invention is:

1. In combination an intake pipe for internal combustion engines, and a rotary mixing device comprising two rotary devices of substantially the same diameter, 50 adapted to be mounted in said pipe and to have the desired clearance therewith, and to be actuated by a common current of flowing fluid to essentially revolve at different rates of speed.

2. In combination an intake pipe for internal combustion engines, and a rotary mixing device comprising two rotary devices of substantially the same diameter, 55 adapted to be mounted in said pipe and to have the desired clearance therewith, and to be actuated by a common current of flowing fluid to essentially revolve at different rates of speed, each consisting of a hub; a common spindle on which said hubs rotate, 60 and a set of vanes carried by each of the said hubs, as set forth and for the purpose specified.

FRANK MOORE.
ALEXANDER GRAY.
